CHAIR BASE

Torris H. Alfreds, Park Ridge, Ill., assignor to
Posture Research Corporation, Elkhart, Ind., a
corporation of Indiana

Application August 10, 1942, Serial No. 454,255

4 Claims. (Cl. 155—138)

This invention relates to improvements in chair bases and it consists of the matters herein-after described and more particularly pointed out in the appended claims.

The base with which the invention is more especially concerned is of the kind used in office chairs and which includes four legs, disposed non-radially with respect to center of the base and with the inner end portions of the legs grouped in encircling relation about the center of the base and each operatively secured to at least two of the other of the legs.

One of the objects of the present invention is to provide an improved construction for the connection between the inner end portions of the legs, which though simple and inexpensive to produce, results in a strong and rigid chair base.

Another object of the invention is to provide an improved construction for the connection between the inner end portions of the legs and in which each of the bolts for the spindle bearing plates are made to perform the added function of securing each two adjacent legs together.

The above mentioned objects of the invention, as well as others, together with the advantages thereof, will more fully appear as the specification proceeds.

In the drawing:

Fig. 1 is a top plan view of a chair base embodying the preferred form of the invention.

Fig. 2 is a side elevation of the base.

Fig. 3 is a vertical section through a part of the base, on an enlarged scale, as taken on the line 3—3 of Fig. 1.

Fig. 4 is a view in side elevation of one of the legs of the base.

Referring now in detail to that embodiment of the invention as illustrated in the drawing, the same includes a plurality of vertically edge-wise disposed counterpart legs 10—10 each made of wood and each of which includes an inner or hub end portion 11 and an outer or caster end portion 12. As shown in Fig. 1, there are four of such legs and the inner end portions 11—11 of all of said legs are grouped in non-radial, encircling relation about the center of the base to there leave a rectangular space or chamber 13, see Fig. 1.

In this instance the inner end portion of each leg has flat sides and projecting from the top margin thereof is a tenon 14 having a horizontal length approximating the thickness of the leg. This tenon, as shown in Fig. 4 may approximate in vertical height about one-half

that of the portion 11 of the leg, thus leaving a bottom margin corner recess 15 with vertical and horizontal surfaces 16 and 17 respectively, the surface 17 forming the bottom edge of the tenon 14. In said top margin of the leg and spaced from the tenon, toward the caster end of the leg, is a mortice recess 18 having a width approximating the thickness or width of the leg and of a depth approximating the vertical height of the tenon 14. Below this recess the inner end portion 11 of the leg has a part 19 which has a vertical height approximating that of the recess 15. Centrally in the tenon 14 and in the part 19 of the leg below the mortice recess 18 are bolt openings 20 and 21 respectively, all as best appears in Fig. 4.

In the assembly of the legs, the tenon 14 of one leg is engaged in the mortice recess 18 of another leg with the bottom edge 17 of the tenon of the first leg engaging the bottom edge of the recess 18 in said another leg, and with the edge 16 of the recess 15 of the first leg engaged flatwise against one face of that part 19 below the recess 18 in said other leg. In this position the inner end portions 11 of the legs are grouped in encircling relation and are disposed non-radially with respect to the center of the base, as best shown in Fig. 1, and the bolt holes 20 in the tenons 14 register with the holes 21 in the parts 19 of said legs. With this arrangement, the tenon of each leg is disposed on one side of the center of the base and mortice recess is disposed on the other side of said center and the inner end portions of all of the legs coact to produce a square hollow hub 22 for the base, which encloses the hollow space 13 before referred to.

At the top and bottom of the hub are square, stiff metal plates 23 and 24 respectively, each having an area approximating that of the hub 22. Each plate has a center hole 25 adapted to receive the seat supporting spindle or post (not shown) of the chair. In each corner of said plates are holes 26 (see Fig. 3) which register with the aligned bolt holes 20 and 21. Bolts 27 are inserted through said holes preferably from the top of the hub so that their threaded bottom ends may receive nuts 28. When the nuts are drawn up tight on the bolts, the legs are rigidly secured together in the proper base forming relation.

It is apparent from the above that each leg 10 is secured by the bolts 27 to two other legs of the group, against displacement or separation in both vertical and horizontal directions. Thus a

strong and rigid light-weight base is provided for the chair, which cannot rack or warp out of shape and in which looseness and resultant squeaks cannot readily develop.

While in describing the invention, I have referred in detail to the form, arrangement and construction of the parts involved, the same is to be considered only in the illustrative sense and therefore I do not wish to be limited thereto except as may be specifically set forth in the appended claims.

I claim as my invention:

1. A chair base embodying therein a plurality of counterpart legs, each including a substantially horizontal inner end portion and an outer end portion, the inner end portion of each leg having a tenon projecting horizontally from and having a vertical height less than that of said inner end portion and defining a part of a recess vertically in line therewith, the inner end portion of each leg also having a recess therein that opens laterally therethrough and is disposed in the horizontal plane and has the vertical depth of and is spaced inwardly from said tenon, there being a bridge vertically in line with the last mentioned recess and which bridge is disposed in the horizontal plane and has the vertical depth of the first mentioned part recess, the said legs being arranged with their inner ends in a grouped relation to form a hollow hub for the base, with the tenon and bridge of each leg engaging in the recess and part recess of two adjacent legs and with the tenon of each leg supportingly engaged with the bridge of another leg, and means passing vertically through each set of engaged tenons and bridges.

2. A chair base embodying therein a plurality of counterpart legs, each including a substantially horizontal inner end portion and an outer end portion, the inner end portion of each leg having a tenon projecting horizontally from and having a vertical height less than that of said inner end portion and defining a part of a recess vertically in line therewith, the inner end por-

tion of each leg also having a recess therein that opens laterally therethrough and is disposed in the horizontal plane and has the vertical depth of and is spaced inwardly from said tenon, there being a bridge vertically in line with the last mentioned recess and which bridge is disposed in the horizontal plane and has the vertical depth of the first mentioned part recess, the said legs being arranged with their ends in a grouped relation to form a hollow hub for the base, with the tenon and bridge of each leg engaging in the recess and part recess of two adjacent legs and with the tenon of each leg supportingly engaged with the bridge of another leg, plate members disposed upon the top and bottom edges of the tenons and bridges of all of said legs, and fastening means passing through each set of engaged tenons and bridges of all of said legs and operatively engaged with said plate members.

3. As an article of manufacture, a leg for a chair base including a substantially horizontal inner end portion and an outer end portion, a tenon projecting horizontally from and having a vertical height less than that of said inner end portion and forming a part of a recess vertically in line therewith, there being a recess laterally through said inner end portion which is spaced longitudinally from and is disposed in the same horizontal plane as and coextensive with said tenon.

4. As an article of manufacture, a leg for a chair base having a substantially horizontal inner end portion and an outer end portion, the inner end portion having upper and lower margins, a tenon projecting from the upper margin of said inner end portion and forming a part of a recess in said lower margin, there being a recess laterally through said upper margin of said inner end portion which is spaced longitudinally from and is disposed in the same horizontal plane and is coextensive with said tenon, a part of the lower margin below said recess being coextensive laterally with the first mentioned part recess.
